UNITED STATES PATENT OFFICE.

FRANK E. NELSON, OF LOS ANGELES, CALIFORNIA, ASSIGNOR TO BELLE O. NELSON, OF LOS ANGELES, CALIFORNIA.

SHOE-POLISHING DEVICE.

1,151,034.

Specification of Letters Patent. Patented Aug. 24, 1915.

Application filed September 22, 1914. Serial No. 862,875.

To all whom it may concern:

Be it known that I, FRANK E. NELSON, a citizen of the United States, residing at Los Angeles, in the county of Los Angeles and

5 State of California, have invented new and useful Improvements in Shoe-Polishing Devices, of which the following is a specification.

My present invention pertains to shoe-polishing devices of the kind including a 10 foot-supporting body, a strip of polishing material, and rods carried by the body and arranged to guide the strip of material in such manner as to carry portions of the 15 same against different portions of a shoe; and it consists in the peculiar and advantageous polishing device hereinafter described and definitely claimed.

In the accompanying drawings, which are 20 hereby made a part hereof: Figure 1 is a perspective illustrating the manner of using my novel device. Fig. 2 is a plan showing the body and the metallic portion of the device. Fig. 3 is a transverse section taken in 25 the plane indicated by the line 3—3 of Fig. 2.

Similar numerals of reference designate corresponding parts in all of the views of the drawing.

30 My invention contemplates the provision of a shoe-polishing device that is extremely simple and inexpensive in construction, and is designed with a view to facilitating the edgewise placing of the strip of polishing material between the body and the side rods, and also with a view to preventing the loop 35 of the strip from running off the toe of the shoe incidental to the polishing of the toe portion of the shoe.

40 The invention therefore consists in a wooden body comprising two superimposed sections 1 connected together by glue or other suitable means, and provided, by preference, on its underside with rubber or other 45 suitable pads 2; a strip 3 of textile material or other material suitable for polishing purposes; side rods 4 spaced from the side edges of the body and having outwardly and rearwardly directed arms 5 at their forward 50 ends, and an upstanding loop-shaped toe stop disposed at the front end of the body.

The upstanding toe stop, which is numbered 6, terminates at its ends in rearwardly extending longitudinal rods 7, the rear ends of which are joined through loops 8 with 55 the rear ends of the side rods 4.

As will be clearly understood by comparison of the several figures, the rods 7 and portions of the loops 8 are interposed between and held by the sections 1 of the body. 60 From this it follows that the side rods 4 and the toe stop 6 are maintained in fixed relation to the body without the employment of extraneous means, which contributes greatly to the cheapness of the device. 65

It will be gathered from the foregoing that the spaces between the side rods 4 and the side edges of the body 1 are open at their forward ends, and therefore the strip 3 can be introduced edgewise between the body 70 and the side rods 4. This is advantageous because it facilitates the placing of the strip 3 relative to the body and the side rods, particularly when the strip 3 is provided at its ends with large handles as is sometimes 75 the case. It will also be gathered that incidental to the use of the device the stop 6 offers an abutment to the toe of the shoe to be polished, and the arms 5 on the rods 6 effectually prevent the loop of the strip 3 80 from running off the toe of the shoe during the polishing thereof. It will further be gathered that making of the stop 6 and the side rods 4 in one piece of wire, as illustrated, and the securing of the unitary metallic element between the sections 1 of the body contributes to both the inexpensiveness 85 and the durability of the device.

Having described my invention, what I claim and desire to secure by Letters-Patent, 90 is:

In a shoe polishing device, the combination with a body comprising superimposed sections, connected together; of an upstanding toe stop, longitudinal rods extending 95 from the ends thereof, side rods, and loops joining the rear ends of the longitudinal rods and side rods; the said toe stop, longitudinal rods, side rods and loops being formed of one piece of material, the longitudinal rods and parts of the loops being 100 interposed and held between the sections of

the body, and the side rods being spaced from the body and provided at their opposite ends, with reference to the loops, with lateral arms constructed and arranged to prevent the bights of a polishing cloth running off the side rods.

5 In testimony whereof I have hereunto set

my hand in presence of two subscribing witnesses.

FRANK E. NELSON.
